UNITED STATES PATENT OFFICE.

LYNDON C. PALMER, OF BUFFALO, NEW YORK, ASSIGNOR TO F. N. BURT COMPANY, LIMITED, OF BUFFALO, NEW YORK, A CORPORATION OF ONTARIO, CANADA.

BOX.

1,221,900.

Specification of Letters Patent. Patented Apr. 10, 1917.

Application filed January 8, 1916. Serial No. 70,933.

To all whom it may concern:

Be it known that I, LYNDON C. PALMER, a citizen of the United States, residing at Buffalo, in the county of Erie and State of New York, have invented certain new and useful Improvements in Boxes, of which the following is a full, clear, and exact description, such as will enable others skilled in the art to which it appertains to make and use the same.

The invention relates generally to boxes, but more particularly to that type of box usually made of paper, and used for holding finely divided material, such as powder.

One object of the invention is to provide a box in which the contents may be effectively carried, and at the same time substantially prevented from sifting out, as happens in devices of different construction.

A further object is to provide a construction whereby the above objects will be attained, and in which the component parts of the device may be readily assembled in preliminary relationship, after which when the box has been filled they may be united permanently by a simple operation.

Other objects of the invention will be in part obvious and in part pointed out hereinafter.

The invention accordingly consists in the features of construction, combination of elements and arrangement of parts which will be exemplified in the construction hereinafter set forth, and the scope of the application of which will be indicated in the following claims.

In the accompanying drawings, forming part of this specification, and wherein similar reference characters refer to similar parts throughout the several views;

Figure 1 represents the lid of a box embodying one form of the invention;

Fig. 2 represents the base thereof;

Fig. 3 represents the cover or container adapted to be fitted within the base;

Fig. 4 is a cross sectional view of the assembled structure; and

Figs. 5 and 6 represent modifications.

Referring now more specifically to the drawings, the numeral 1 indicates a box head and 2 a box flange secured to the head, these two elements forming a box, or base, and being preferably made of relatively stiff material such as cardboard, strawboard, etc., as is usual in paper boxes. This box is to

be assembled with a protective lid 3, made of similar material, this lid being adapted to retain the contents of the box. There will be a joint, as at 4, between the lid and box, and when the box contains finely divided material, as, for instance, face powder, some of it may drift through this joint, resulting in loss of powder and soiling of surrounding objects. One of the main objects of the present invention is to avoid or minimize this loss, and to retain the powder in that part of the box provided therefor. To this end a box element, or cover, is provided which overlies the contents of the box between the lid and the base.

The overlying portion, or head, of this cover is indicated at 5, in Fig. 3, being made of an imperforate frangible fabric, as thin paper; and at 6, in Fig. 5, where it is made of thin paper twisted or interfolded so as to confine the powder therebeneath, but which may be unfolded to permit access to the powder. The form illustrated in Fig. 3 is preferred, and the further description will be directed more particularly thereto, reference being made to the similar parts of other forms, where the context requires.

The cover is mounted on the box preferably inside thereof, as shown, and sealing or packing material is interposed between the box and cover where these parts are joined. In the preferred embodiment this sealing material is disposed between the box and cover, and preferably between the flanges of such elements. In Fig. 3 the packing or sealing material is indicated at 7, where it is formed by an extended portion of the material of the frangible head 5, whereas in Fig. 5, it is a continuation of the twisted or folded head 6, and indicated at 8. In each

form illustrated the sealing material is adhesively secured to the box, preferably to the flange thereof, thereby practically preventing the powder drifting out at the joint. The head 5 is composed of any suitable frangible material; that is, material which may be readily ruptured or perforated or torn, as by pressing thereon with a finger of the hand.

In order to brace the sealing fabric so as to restrain it peeling away from the box flange, and to assist in holding this material adjacent the joint between it and the box, a brace member is employed. In Fig. 5, this member is indicated at 9, lying on

the folded fabric around the inside of the box, whereas in Fig. 3 the brace member comprises a multiple-ply flange of the cover, the plies of which are indicated at 5 10 and 11, the material of the head of the cover extending down between these plies, and at the lower part being folded so as to extend to position between the lower edge of the ply 10 and the head 1, underlying 10 said ply and thence extending upwardly, as at 7, the outer ply 10 thus extending into the fold of the sealing fabric. The plies 10 and 11 are made of relatively stiff material, like that of the box, and serve to stiffen 15 and shape the flexible paper of which the head of the cover is made, so that the downwardly extending side portions of the thin cover paper are held in upright position. Thus in the preferred embodiment shown 20 in section in Fig. 4, the flange of the cover comprises a relatively stiff member lying within and fitting the flange of the box, and extending upwardly above the upper edge 12 of the flange of the box, so as to form a neck over which fit the sides of the lid.

In preferred practical operation, the base, cover and lid are assembled, as shown in Fig. 4, with the sealing fabric not fastened to the base, and they are shipped to 30 the dispenser in this condition. In order that the frangible head 5 may not be accidentally punctured or broken, the covers may, at this time, be provided with a reinforcing head 13, underlying the head 5, and fitting inside of the cover flange. The dispenser removes the lid, the cover, and the reinforcing head 13, fills the receptacle with powder, applies adhesive to the outside of 35 the lower portion of the outer ply 10 and to the sealing material at 7, and replaces the cover and the lid, omitting the head 13. The adhesive soon sets, the cover being thus fastened to the box in a manner to practically prevent the escape of powder out of 40 the containing chamber until the box is operated in the manner intended by the user.

In boxes wherein the cover flange fits tightly in the box flange, the adhesive may be dispensed with, as the sealing material 50 will restrain the escape of powder, and the tight fit will hold the parts in assembled position.

In Fig. 6, is illustrated a further modification wherein sealing or packing material, as raw cotton, felt 14 etc. is inserted between the cover flange and the box flange. The lid 3 cooperates with the base to close the box, and in the present embodiment the flange 15 of the lid surrounds the cover 55 flange and makes a joint 4, with the upper edge of the box flange 2.

Thus by the above described construction are accomplished, among others, the objects hereinbefore mentioned.

65 As many changes could be made in the

above construction and many apparently widely different embodiments of this invention could be made without departing from the scope thereof, it is intended that all matter contained in the above description or 70 shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween. 80

Having described my invention what I claim as new and desire to secure by Letters Patent is:

1. In a device of the character described, in combination, a box, a frangible head having a stiff flange fitting the flange of the box, and a removable reinforcing head beneath and supporting said frangible head. 85

2. In a device of the character described, in combination, a box, a frangible head having a stiff flange fitting the flange of the box, a removable reinforcing head beneath and supporting said frangible head, and a lid overlying said frangible head and said reinforcing head, and having a flange fitting the first mentioned flange. 90

3. In a device of the character described, in combination, a box, a cover for the material in the box, a folded sealing fabric connecting the box and cover and adapted to prevent the escape of material from the box where so connected, and a brace lying on the fold of said fabric. 100

4. In a device of the character described, in combination, a box, a cover for the material in the box, a folded sealing fabric connecting the box and cover and adapted to prevent the escape of material from the box where so connected, and a cover stiffening member extending into the fold of said 110 fabric.

5. In a device of the character described, in combination, a box, an imperforate frangible cover for the material in the box, and a foldable sealing fabric connecting the box 115 and cover inside the box and adapted to prevent the escape of material from the box where connected to the box.

6. In a device of the character described, in combination, a box, a cover for the material in the box, a folded sealing fabric connecting the box and cover inside the box and adapted to prevent the escape of material from the box where so connected, and a brace lying on the fold of said fabric inside the box. 125

7. In a device of the character described, in combination, a box comprising a head and a flange, a cover comprising a frangible head and a relatively stiff flange, the 130

flange of said cover fitting the flange of said box, and packing disposed between said flanges.

8. In a device of the character described, 5 in combination, a box comprising a head and a flange, a cover comprising a frangible head and a relatively stiff multiple-ply flange, the flange of said cover fitting inside the flange of said box, said frangible 10 material extending between the plies of said cover flange and to position between the edge of one of said plies and the head of said box.

9. In a device of the character described, 15 in combination, a box comprising a head and a flange, a cover comprising a frangible head and a relatively stiff multiple-ply flange, the flange of said cover fitting inside the flange of said box, said frangible 20 material extending between the plies of said cover flange around the edge of one of said plies and between said flanges.

10. In a device of the character described, in combination, a box comprising a head and 25 a flange, a cover comprising a frangible head and a relatively stiff multiple-ply flange, the flange of said cover fitting inside the flange of said box, said frangible ma-

terial extending between the plies of said cover flange around the edge of one of said 30 plies and between said flanges, and adhesively secured to said box flange.

11. In a device of the character described, a box element comprising, in combination, a two-ply flange, and a frangible head, the 35 material of the head extending between the plies of the flange, and underlying the edge of one of said plies.

12. In a device of the character described, in combination, a box comprising a head 40 and a flange, a cover comprising a frangible head and a relatively stiff multiple-ply flange, the flange of said cover fitting inside the flange of said box, said frangible material extending between the plies of said 45 cover flange and to position between the edge of one of said plies and the head of said box, and a protective lid overlying said frangible head and having sides adapted to surround said cover flange.

In testimony whereof I affix my signature, in the presence of two witnesses.

LYNDON C. PALMER.
